UNITED STATES PATENT OFFICE.

EDGAR H. CLARK, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE SYSTEM.

Application filed December 4, 1919. Serial No. 342,412.

To all whom it may concern:

Be it known that I, EDGAR H. CLARK, a citizen of United States, residing at New York, in the county of New York, State of New York, have invented certain new and useful Improvements in Telephone Systems, of which the following is a full, clear, concise, and exact description.

This invention relates to telephone exchange systems and more particularly to systems involving the use of selective signaling apparatus for operating the signaling devices on subscribers' lines.

In telephone systems in which a transition is taking place from the manual method of establishing connections to the use of automatic switches for accomplishing that purpose, it is desirable that certain offices be equipped with both call indicator trunks and manual connecting circuits at final operators' positions. A call indicator is arranged in the usual manner in common to the incoming trunks from an automatic office, and may be assigned by the final connecting operator to any trunk at her position on which a call appears. If party lines are to be served, an indication is first produced on the indicator to inform the operator of the called line number. Also a ringing selection condition is automatically set up on apparatus individual to the trunk to determine the application of the proper kind of ringing current to operate the called subscriber's bell on the party line when the operator completes the connection.

When, however, a call is extended from a distant manual office over one of the manual connecting circuits at the operator's position, it is necessary to provide means whereby the operator may cause the application of the proper character of current to ring the called substation bell on the party line. It has been common practice to equip manual circuits of this character each with a set of ringing selection keys so that when a call is completed by any of these circuits the actuation of the keys individual to that circuit applies the necessary ringing current. Where, as in systems of the character above outlined, it is necessary to assemble at the same operator's position call indicator trunks and manual connecting circuits, the expedience of securing a uniformity of the acts performed by the operator in handling both types of calls becomes obvious. More-

over, it is desirable that the construction and operation of the ringing equipment of the manual circuits be made to closely conform with that required for call indicator trunks. By this means the conversion of manual connecting circuits to call indicator trunks may be obtained with comparatively few changes and alterations.

Accordingly, it is the object of this invention to provide ringing selection devices common to a group of connecting circuits at an operator's position by means of which the operator may control the application of a plurality of kinds of ringing current to subscribers' lines.

A feature of the invention relates to the provision of a common key set, arranged to be associated with any of a plurality of connecting circuits by manual means individual to each circuit, and by means of which keys a plurality of relays are operable in variable combinations to set up and maintain a plurality of ringing selection conditions.

Other features and advantages of this invention will become apparent from a consideration of the following description and appended claims.

In the drawing there is indicated at the left of the vertical broken line an A operator's position in a manual office, from which position outgoing connecting circuits lead to a distant office. Fig. 1 shows a cord circuit used by the A operator in extending connections to the outgoing connecting circuits. Fig. 2 shows in detail the incoming end of one of these connecting circuits terminating at a B operator's position in the distant office, together with a party line to which connections are extended by the B operator. This figure also shows a portion of a second one of the incoming connecting circuits from the distant A operator's position.

According to the system in which this invention is embodied, a final connecting or B operator's position is equipped with a plurality of connecting circuits incoming from a distant office by means of which the B operator completes the extension of calls to party lines appearing in multiple jacks at her position. A set of ringing selection keys is provided in common to all the connecting circuits at the B operator's position for the purpose of determining the proper character of ringing current to be applied to a

party line for ringing the bell at the called substation on that line. Each of the several connecting circuits is provided with an individual assignment key, the operation of which associates the common set of ringing selection keys with the corresponding connecting circuit. For each of the connecting circuits there is also arranged a set of ringing selection relays which are operable in variable combinations under the control of the common key set, when associated with that particular connecting circuit. These sets of relays, when once energized in the combination determined by the actuation of the common keys, are locked up and remain energized independently of said common keys. When the plug of the connecting circuit over which the call has been extended is inserted in the jack of the called line the common set of ringing keys is automatically disassociated from the connecting circuit and is then free to be associated with other circuits. The ringing selection relays now serve to cause the application in the proper manner of one of two sources of ringing current to the party line to operate the bell at the called substation to the exclusion of the bells at the other substations.

In the drawing there are shown only the detailed circuits of one of the four subscribers' stations on the party line. The other three substations are illustrated diagrammatically. In order to secure the necessary number of ringing combinations with the use of two sources of ringing current of different character, the call bells at two of the subscribers' stations are connected from the tip side of the line to ground. The bells at the other two subscribers' stations are connected from the ring side of the line to ground. These bells are constructed to operate on the biased principle, a bell on each of the tip and ring sides of the line responding only to positive current and the remaining two bells on the tip and ring side responding only to negative current.

In the following detailed description of the operation of the system disclosed, it will be assumed that a call, either originating at, or having been extended from other offices to the A operator's position, illustrated at the left of the vertical broken line in the drawing, is to be further extended to a party line served through the B operator's position. It will further be considered that the calling party wishes to converse with the subscriber at substation 200 on the party line. When the call is initiated, the A operator responds to the same in the usual manner by inserting answering plug 101 in the jack (not shown) of the subscriber's line or of the trunk circuit incoming to her position, as the case may be. Upon the number of the called line and the station's designation being com-

municated to her, the A operator converses with the B operator in the called office by means of the usual order wire (not shown). In her conversation with the B operator the A operator communicates to her the number of the called line and the designation of the wanted station thereon, and also requests the assignment of a connecting circuit for the purpose of extending this connection. The A operator is then notified that a connecting circuit, such as the one shown in detail in Fig. 2, is idle and may be taken for use. Accordingly the A operator inserts the plug 102 of her cord circuit in the jack 107 of the assigned connecting circuit leading to the B operator's position in the called office. Upon the insertion of the plug 102 in jack 107 a circuit is closed from battery through supervisory lamp 105, relay 103, sleeve of plug 102, sleeve of jack 107 to ground. Lamp 105 is illuminated by the current flowing in this circuit. Relay 103 becomes energized and completes a circuit from ground through the upper right-hand winding of repeating coil 106, front contact and armature of relay 103, tip of plug 102, tip of jack 107, outer right-hand armature and contact of relay 208, upper left-hand winding of repeating coil 231, left-hand winding of relay 204 to battery and ground. Relay 204 completes a circuit from ground through its armature and contact, winding of relay 205 to battery and ground. Relay 205 by energizing closes a circuit from ground through its inner right-hand armature and front contact, inner-left-hand armature and contact of relay 228, back contact and right-hand armature of relay 207, assignment lamp 209 to battery and ground. The illumination of lamp 209 in this circuit advises the B operator that the connection has been extended to the assigned trunk in the calling office. The B operator now depresses an assignment key 206 individual to the connecting circuit. Key 206 establishes a circuit from ground through its closed contact, right-hand winding of relay 207, outer left-hand armature and contact of relay 228 to battery and ground. Relay 207 becomes energized and closes a substitute locking circuit for itself through both of its windings in series and its inner left-hand armature and contact to ground. The operation of relay 207 disconnects the assignment lamp 209 from the armature and front contact of relay 205 and connects it to the interrupter 211. The interrupter 211 causes the intermittent illumination and extinguishment of lamp 209 so long as relay 207 remains energized. Relay 207 also closes a circuit at its outer left-hand armature and contact for the relay 208. Relay 208 by attracting its right-hand armature opens the above traced circuit for relay 204 120 and the station's designation being com-

permitting relays 204 and 205 to retract their armatures. Relay 208 at its left-hand armatures associates the common non-locking keys 210, 220, 230 and 240 by way of conductors 232 and 233 with the connecting circuit over which the call has been extended.

The operator having learned that a conversation is desired with the subscriber at 10 substation 200, depresses the key 230 to set up a condition for the application of the proper character of ringing current to cause the operation of the bell at that substation. The actuation of key 230 completes a circuit from ground through the left-hand contact of said key, conductor 233, inner left-hand armature and contact of relay 208, conductor 234, winding of relay 212 to battery and ground. Relay 212 energizes and completes a circuit for itself from battery through the winding and contact and inner right-hand armature of said relay, conductor 236 to ground at the contact and outer left-hand armature of relay 215. Relay 212, therefore, remains energized independent of the common ringing key 230.

The operator then seizes the plug 226 of the connecting circuit and inserts it in the jack 227 of the called line. The insertion 30 of plug 226 in the jack 227 causes a circuit to be closed from ground through the winding of relay 225, sleeve of jack 227, sleeve of plug 226, conductor 237, winding of relay 224 to battery and ground. In parallel 35 to this circuit a circuit is also closed for relay 228. Relay 224 at its right-hand armature closes the tip conductor 238 of the connecting circuit. Relay 224 also closes a circuit from battery through the winding of relay 212, contact and inner right-hand armature of relay 212, contact and inner left-hand armature of relay 224 to ground. This 40 circuit serves to maintain the energization of relay 212 independently of the relay 215. Relay 228, which also energizes in parallel with relay 224, opens the above 45 traced circuit for relay 207. Relay 207, therefore, releases its armatures and opens the circuit of lamp 209, whereby said lamp 50 ceases to flicker. Relay 207 at the same time opens the energizing circuit of relay 208, which latter relay, by releasing its armatures, disassociates the common ringing keys 210, 220, 230 and 240 from the connecting 55 circuit.

Relay 208 at its right-hand armatures completes the tip and ring sides of the connecting circuit through to the repeating coil 231. Relay 204, therefore, becomes energized again in the circuit above traced 60 through its left-hand winding to ground at the repeating coil in the A operator's cord circuit, shown in Fig. 1. The energization of relay 204 in turn causes the 65 energization of relay 205 as described. Re-

lay 228 also completes a circuit from battery through the disconnect lamp 217, contact and right-hand armature of relay 228, contact and armature of relay 214, back contact and right-hand armature of relay 221, winding of relay 223 to ground. Relay 223 attracts its armature and connects the tip and ring conductors 238 and 239 to the left-hand armatures of relay 212. Relay 221 is also included in a branch parallel 75 to the circuit just traced but does not energize since it is shunted out by the path leading through the contact and armature of relay 214. The disconnect lamp 217 does not receive sufficient current in series with 80 relay 223 to become illuminated. As soon after the energization of relay 205, which takes place as shown following the insertion of the plug in the jack, as a conducting segment of the pick-up interrupter 216 85 makes engagement with its cooperating brush, a circuit is closed for the pick-up relay 215. This circuit leads from battery through the interrupter 216, normally closed right-hand contact of relay 215, winding 90 of said relay, contact and left-hand armature of relay 205, contact and outer left-hand armature of relay 224, to ground. Relay 215 energizes and locks up in a circuit closed through its inner right-hand 95 armature and make-before-break contact. With the ringing relay 223 and the pick-up relay 215 both energized, the ringing circuit is completed for the application of negative current to the tip side of the 100 called line. This circuit may be traced from the ringing source 219 through the left-hand winding of relay 214, back contact and left-hand armature of relay 213, outer right-hand armature and contact of 105 relay 215, front contact and inner left-hand armature of relay 212, front contact and inner armature of relay 223, conductor 238, front contact and right-hand armature of 110 relay 224, tip of the plug 226, tip of the jack 227 over the tip side of the party line, winding of relay 241 at the desired substation, and then returning by way of the ring side of the party line, ring of the jack 227, ring of plug 226, conductor 239, outer 115 armature and front contact of relay 223, outer left-hand armature and front contact of relay 212 to ground. Relay 241 responds to the first impulse of current over this circuit, and by attracting its armature 120 closes a circuit from the ringing source 219 over the tip side of the line directly to ground through the windings of biased ringer 242. The bell 242 operates in response to current flowing in this circuit to 125 the exclusion of the bells at the other substations on the party line.

When the called subscriber responds by removing his receiver from the switchhook, a low resistance path is closed through the 130

- switchhook contacts which permits the energization of the marginal relay 214 in series with the source of ringing current. Relay 214 by attracting its armature opens the short circuit around the winding of relay 221. Relay 221, therefore, energizes in series with the disconnect lamp 217 and relay 223. Relay 221 at its right-hand armature and front contact closes a locking circuit for itself in series with the lamp 217, which causes the shunting of relay 223 and the consequent deenergization thereof. The disconnect lamp 217, however, still remains extinguished due to the resistance of relay 221. Relay 223 on retracting its armatures completes the tip and ring sides of the connecting circuit through to the right-hand windings of the repeating coil 231. A circuit is, therefore, established from battery through the lower right-hand winding of repeating coil 231, winding of supervisory relay 222, back contact and outer armature of relay 223, conductor 239, ring of plug 226, ring of jack 227 over the loop of the called substation, tip of jack 227, tip of plug 226, right-hand armature and front contact of relay 224, conductor 238, inner armature and back contact of relay 223, upper right-hand winding of repeating coil 231 to ground. The supervisory relay 222 energizes in this circuit and completes a circuit from battery through the lower right-hand winding of the repeating coil 106 in the A operator's cord circuit, winding of supervisory relay 104, ring of plug 102, ring of jack 107, inner right-hand armature and contact of relay 208, lower left-hand winding of repeating coil 231, right-hand winding of relay 204, armature and contact of relay 222, left-hand armature and contact of relay 221 to ground. Relay 204, therefore, remains energized by means of circuits closed through both its windings and the windings of repeating coils 231 and 106. The supervisory relay 104 by attracting its armature closes a direct circuit from battery through the winding of relay 103 to ground at the sleeve of jack 107. This circuit shunts out the supervisory lamp 105 which becomes extinguished to advise the A operator that the called subscriber has answered.
- If, after the called subscriber has replaced his receiver on the switchhook and before the B operator has removed plug 226 from the called line jack 227, the A operator wishes to rering the called subscriber, she may do so by momentarily disconnecting the plug 102 from jack 107. The removal of plug 102 from jack 107 opens the energizing circuit of relay 204. Relay 204 in turn causes the deenergization of relay 205. Relay 205 by retracting its armatures closes a circuit from battery through disconnect lamp 217, contact and right-hand armature of relay 228, back contact and outer right-hand armature of relay 205 to ground. This direct circuit to ground in series with lamp 217 shunts out the relay 221, which releases its armatures. When the plug is again inserted in jack 107, relays 204 and 205 again become energized. The original circuit, including lamp 217, the back contacts and armatures of relays 214 and 221, and the winding of relay 223 is thereupon closed. Relay 223 energizes and ringing current is supplied to the called line in the same manner as already described.
- When the conversation is finally completed and the called subscriber replaces his receiver on the switchhook, relay 222 deenergizes and opens the circuit above traced for the supervisory relay 104 in the A operator's cord circuit. Relay 104 retracting its armature removes the shunt from around supervisory lamp 105. Lamp 105 becomes lighted to inform the operator that the connection is no longer desired. She then withdraws the plug 102 from the jack 107. This opens the circuit through the left-hand winding of relay 204. Relay 204 deenergizes and causes the deenergization of relay 205. The above traced circuit is then completed for the disconnect lamp 217 to ground at the back contact and outer right-hand armature of relay 205. The B operator observing the steady illumination of the disconnect lamp knows that the conversation has been completed and proceeds to remove the plug 226 of the connecting circuit from the jack of the called line. The removal of the plug 226 permits the deenergization of relays 224 and 228, relay 224 in turn permitting the deenergization of relay 212. All apparatus has thus been restored to its normal condition.
- In the establishment of the above described connection, it was assumed that the party at substation 200 was desired, the bell at this substation being responsive only to negative current on the tip side of the line. Had it been required to ring the bells at any of the other three substations, the operator would have actuated the proper one of the common keys to set up the condition of applying the necessary character of ringing current to the line. For example, to apply positive current to the ring side of the line she would depress key 220. The actuation of this key closes a circuit from ground through its closed contacts, conductor 232, outer left-hand armature and contact of relay 208, conductor 235, through the winding of relay 213, to battery and ground. Relay 213 energizes and locks up in the manner already described in connection with the relay 212. When the plug is inserted in the jack, the relay 213 being energized, positive current is connected to the ring side of the line in an obvious manner. To apply positive current to the tip

side of the line the operator depresses key 240, which causes the energization of both relays 212 and 213. To send negative current over the ring side of the line none of the keys 220, 230 and 240 need be operated.

Should the operator discover after having actuated one of the keys 220, 230 or 240 to set up a given ringing condition that she had inadvertently selected the wrong key, the improper ringing condition may be erased by the depression of key 210. The operation of key 210 closes circuits from battery over either conductors 234 or 235 or both, contact and inner right-hand armature of either relay 212 or relay 213 or both, dependent upon the combination of these relays energized, to ground at the contact and outer left-hand armature of relay 215. These circuits shunt out whichever of the relays 212 or 213 happen to be energized to permit their release. The operator then proceeds to operate the proper key to again set up the ringing condition.

It will be observed that when ringing current is to be applied to the tip side of a party line, the ringing circuit for the application of the necessary kind of current leads through the outer right-hand armature and contact of relay 215. The reason for this expedient is to prevent the closure of the ringing circuit until after the plug has been fully inserted in the jack. Should the sleeve of the plug make contact with the sleeve of the jack during the period that the tip of the plug is in contact with the ring of the jack, a brief impulse of ringing current would be momentarily transmitted over the ring side of the line were the ringing circuit completed at this time. To obviate this the ringing circuit is made dependent, as explained, upon the operation of relay 215. Relay 215 cannot become energized until the sleeve relay 224 has been energized and until the pick-up interrupter 216 has advanced one of its metallic segments into engagement with the cooperating brush. This feature greatly reduces the probability that a ringing current will be inadvertently sent over the ring side of the line when calls are being made to subscribers whose bells are connected to the tip side of the line.

If while the connecting circuit, shown in detail, is in use the B operator is advised that a second call is awaiting her attention, she assigns another idle connecting circuit, such as the one illustrated within the broken rectangle shown in the drawing, by depressing the assignment key 244 individual to this connecting circuit. The relay 245 is operated to cause the operation of relay 246 in the manner above described. Relay 246 causes the association of the common key set and the operator proceeds to set up the ringing combination necessary to signal the desired party on the called line.

What is claimed is:

1. In a telephone system, an operator's position, a plurality of connecting circuits thereat, switches for extending said connecting circuits, a set of keys common to said circuits, an individual key for each circuit for associating the common keys with said circuits, a plurality of sources of current, a plurality of relays, means controlled by said common keys for operating a variable number of said relays to connect any of said sources of current to one of the connecting circuits, and means responsive to the operation of one of said switches for disassociating the common key set from the connecting circuit. 70

2. In a telephone system, an operator's position, a plurality of connecting circuits thereat, a manually operable switch individual to each circuit for extending such circuit, a set of keys common to said connecting circuits, individual keys, one for each circuit for associating the common key set with any one of said circuits, a plurality of sources of current of different character, a plurality of relays, means controlled by said common keys for operating a variable number of said relays to connect any of said sources of current to one of said connecting circuits, and means responsive to the operation of one of said switches for disassociating the common key set from the corresponding connecting circuit. 85

3. In a telephone system, an operator's position, a plurality of connecting circuits 100 thereat, a set of keys common to said circuits, individual keys, one for each circuit for associating said common keys with any one of said circuits, a plurality of sources of current, a plurality of relays, means controlled 105 by the common keys for operating a variable number of said relays to connect any of said sources to one of said circuits, means for maintaining the connection of one of said sources of current to the connecting circuit 110 independent of said keys, and means controlled by the connecting circuit for disassociating the common keys therefrom. 110

4. In a telephone system, an operator's position, subscribers' lines terminating in jacks at said position, a group of connecting circuits terminating in plugs at said position for extending connections to said lines, a set of keys common to said circuits for associating said set of keys with a desired one of said connecting circuits, a plurality of sources of current, a plurality of relays, means responsive to the actuation of said common keys for operating a variable number of said relays to connect any of said sources to said circuit, means for maintaining the connections of said sources of current to the connecting circuit independent 120 of said keys, and means responsive to the 125

insection of the plug of said connecting circuit in the jack of a subscriber's line for disassociating said set of common keys from the connecting circuit.

- 5 5. In a telephone system, an operator's position, subscribers' lines terminating in jacks at said position, a group of trunks terminating in plugs at said position for extending connections to the subscribers' lines,
- 10 an individual assignment key for each of said trunks, a set of keys common to said trunks, means responsive to the actuation of one of said assignment keys for associating the common set of keys with the correspond-
- 15 ing trunk, a plurality of sources of ringing current of different character, a set of relays individual to said trunk, means controlled by said common set of keys for operating a variable number of said relays,
- 20 means controlled by said relays for variably connecting any of said sources of current to said trunk, means for maintaining said relays in their operated condition independent of said common keys, means responsive to
- 25 the insertion of the plug of said trunk in the jack of a subscriber's line for applying said sources of current to said line; and means responsive to the insertion of said plug in the jack for disassociating the common key
- 30 set from said trunk.

6. In a telephone system, an operator's position, a plurality of connecting circuits thereat, each terminating in a manual switch serving to extend said circuits, a set of ringing keys common to said circuits, individual keys, one for each circuit for associating the common keys with any one of said circuits, a plurality of sources of ringing current, a plurality of relays, means controlled by the
- 35 common keys for operating a variable number of said relays to connect any of said sources to one of said circuits, and means responsive to the operation of one of said manual switches for disassociating the common keys from the corresponding connecting circuit.

7. In a telephone system, an operator's position, a telephone line, a plurality of connecting circuits at the operator's position for extending connections to said line, a set of keys common to said circuit, individual keys, one for each circuit for associating

said common keys with any one of said circuits, a plurality of sources of current, a plurality of relays, means controlled by the common keys for operating a variable number of said relays to connect any of said sources to one of the connecting circuits, means for maintaining the connection of said sources of current independent of said keys, means responsive to the connection of a connecting circuit to said line for disassociating said common keys from such circuit, and means controlled over said line for disconnecting said sources of current from the connecting circuit.

8. In a telephone system, an operator's position, a subscriber's line, a plurality of connecting circuits at the operator's position for extending connections to said line, a set of keys common to said circuits, individual keys, one for each circuit for associating said common keys with any one of said circuits, a plurality of sources of current, a plurality of relays, means controlled by the common keys for operating a variable number of said relays to connect any of said sources to one of the connecting circuits to signal the subscriber's line, means for maintaining the connection of said sources of current independent of said keys, means responsive to the connection of a connecting circuit to said line for disassociating said common keys from such circuit, and means operated by the response of the subscriber for disconnecting said source of current from the connecting circuit.

9. In a telephone system, an operator's position, a plurality of connecting circuits thereat, switches for extending said connecting circuits, a set of keys common to said circuits, an individual key for each circuit for associating the common keys with said circuits, a plurality of sources of current, means controlled by said common keys for connecting said sources of current to one of the connecting circuits, and means responsive to the operation of one of said switches for disassociating the common key set from the connecting circuit.

In witness whereof, I hereunto subscribe my name this 28th day of November A. D., 1919.

EDGAR H. CLARK.
